TYPE CASTING MACHINE

George Herbert White, Hartford, Conn., assignor
to Chester A. Macomic, Chicago, Ill.

Application September 28, 1933, Serial No. 691,296

19 Claims. (Cl. 199—7)

My invention relates to improvements in type-casting or type setting machines. It has for one object to provide in connection with such a machine wherein letter carrying members are mounted for movement along lines other than horizontal, means for automatically holding the type carrying members in place during a part of the operation.

Another object is to provide means in combination for longitudinally displacing a plurality of bars or matrix strips, arresting the movement of each strip in a predetermined position, aligning the characters on or associated with or controlled by the various strips in register with a mold, squeezing the strips against the mold and then releasing the strips while holding them against downward movement until the longitudinal moving means has had time to pick up each successive strip as it returns to the starting position.

While my device is applicable to many different types of type selecting, casting or setting machines, I have illustrated it in connection with a type casting machine wherein a plurality of matrix strips are mounted on an inclined bed, these strips being associated with propelling means which draw them down in the same direction they would travel under the influence of gravity and propelling means releasing successive strips when the strip reaches a point at which the desired character on the strip is in line with the mold or other place where it is to be used. The propelling means having released each strip, other means come into operation to hold the strip in place during the casting or printing act. When those holding means let go, the strips may fall freely by gravity until they reach the propelling means on its upward movement. In order to prevent this, my invention concerns itself primarily with automatic means which hold each individual strip against the force of gravity after the rectifying and holding means during the casting act have been released and before the propelling means have engaged each individual strip.

My invention is illustrated more or less diagrammatically in the accompanying drawings, wherein—

Figure 1 is a side elevation with parts omitted;

Figure 2 is an enlarged longitudinal section through the machine showing parts in section and parts in elevation;

Figure 3 is a section on an enlarged scale along the line 3—3 of Figure 1;

Figure 4 is a detail view similar to Figure 2 but

with parts omitted and showing the parts in different positions;

Figure 5 is a plan view of part of the mechanism shown in Figure 4 with parts omitted;

Figure 6 is an enlarged section along the line 6—6 of Figure 3;

Figure 7 is an enlarged section along the line 7—7 of Figure 4;

Figure 8 is a section along the line 8—8 of Figure 7;

Figure 9 is a section similar to Figure 4 showing the modified form;

Figure 10 is a section similar to Figure 9 showing the parts in a different position;

Figure 11 is a detail view similar to Figure 5 showing a modified form.

Like parts are indicated by like characters throughout the specification and drawings.

A is a base having an upright frame A¹ projecting therefrom and carrying a transmission box A² adapted to contain a suitable motor and transmission mechanism. Extending from one end of the base A to the upright frame A¹ is a typewriter supporting frame A³ carrying a typewriter A⁴. A⁵ is a pattern bed, A⁶ a matrix bed, 20 the pattern bed having a plurality of pattern pins A⁷ adapted to be selectively projected therefrom by manipulation of the typewriter keys. The operative means therefor are not shown because they form no part of this invention, until the stop pins project into the paths of the latch heads A⁸ on the matrix strips A⁹ which are arranged on their edges side by side for longitudinal movement along the inclined path on the matrix bed A⁶.

B is a drive carriage adapted to travel along the sides of the matrix bed being driven by means of a lever B¹ and pivoted at one end on the base A. Connected at the other end to the drive carriage by means of the link B², a crank B³ having a roller B⁴ engages a slot B⁵ in the drive lever. Rotation of the crank causes reciprocation of the drive carriage B carrying with it the notched pull bar B⁶ along the matrix bed. B⁷ is a latch in the latch head A⁸ in the matrix strip or bar adapted to engage the notch in the drive plate B⁶. This latch is pivoted in the head, the spring B⁸ holding it yieldingly against engagement and disengagement of the notched portion of the drive plate whereby the matrix strip may be caused to reciprocate by 50 reciprocation of the drive carriage and plate.

It will be noted that the matrix bed A⁶ is cut away intermediate its ends to permit the two mold parts C C¹ to be locked in engagement with the moving matrix strips. C² is the pot mouth which 55

may be forced upwardly by means not here shown to force the mold against the matrix strips. C³ is a squeeze frame extending across the matrix bed above the mold and it has a squeeze bar C⁴ which may by outside means not here shown be forced down against the matrix strips in opposition to the upper forcing of the pot mouth so that the strips may be squeezed together and squeezed against the mold for casting. C⁵ is a lower and C⁶ an upper aligning bar adapted to engage the serrations C⁷ on the back side of each strip for the purpose of aligning the characters in the notches C⁸ in the under or working side of the strips A⁹. The specific mechanism for operating these aligning bars as well as many of the other features above referred to form no part of the present invention and are not here illustrated, except that it will be noted that a sprocket C¹⁵ is driven by means in the transmission housing, 10 and drives the chain C⁹ which in turn drives the sprocket C¹⁰ which sprocket drives a gear C¹¹ in mesh with the gear C¹² on the cam shaft C¹³ from which the squeeze mechanism and the aligning bars may be operated by any suitable connection not here shown.

D is a latch bar. It extends across the frame above the matrix strips. Carried on this latch bar on a forward extension thereof are a plurality of pawls D¹ loosely pivoted on a pin D² and held in 30 the socket formed by the underside of the latch bar and the removable cover plate D⁴. There is preferably one of these pawls for each matrix strip. Each pawl has a downwardly extending tooth D⁵ adapted to engage one of the serrations 35 C⁷ and when in the position shown in Figure 4, these pawls are pushed down by the spring D¹² as indicated and prevent downward displacement of the matrix strips when they are released by the lock up. When in the position shown in Figure 2, 40 the pawls are lifted out of engagement. This is accomplished by means of a pivotally mounted spring bar D⁶ having a plurality of spring fingers D⁷ projecting forwardly into engagement with the apertures D⁸ on the ends of the pawls. D⁹ is a 45 lever associated with the pivotally mounted spring bar having a roller D¹⁰ in engagement with the cam D¹¹ on the cam shaft C¹³. D¹² is a spring anchored at one end on the member D, at the other end on an extension D¹³ of the lever tending 50 to hold the roller against the cam and so when the cam permits it to force the springs into the down position to permit the pawls to engage by gravity with the serrated matrix strips. When in the up position the cam exerts a tension 55 on the spring D¹², lifts the lever D⁹ up and the springs D⁷ lift the pawls into the upper position as shown in Figure 2.

The spring bar is supported on the latch bar by means of the adjustable screw pins E engaging 60 adjustable trunnions E¹ in the latch bar whereby a wide range of transverse adjustment of the spring bar with its associated springs is permitted to assure alignment of the latches and the springs.

In Figures 7 and 8 is shown the method of supporting the springs on the spring bar. The flat plate E² being in opposition to the notched edge E³ of the spring bar D⁶, each spring being held between the two in the notch, the plates being drawn together by the cap screw E⁴ thus providing for a simple, convenient adjustment or removal of the springs.

It will be understood that as the pull bar makes its downward excursion and the successive matrix strips are engaged by the stop pins and so caused 75 to be detached from the drive plate, that it is

only when this operation has been completed that the aligning bars come into operation to, if necessary, move the matrix strips down slightly to bring them in alignment with the mold. Thereafter the mold and the squeeze bar are brought together and still later the pattern pins are moved out of line with the matrix strips. While the casting operation takes place, that is, immediately after the squeeze has been started and the strips no longer need to move, the control cam for the latch mechanism in its angular excursion permits the latches or dogs to assume the position shown in Figure 4 which they retain while the casting is taking place and after the squeeze pressure has been removed and after the aligning bars have 10 been removed from engagement with the matrix strips until the drive plate has picked up all the matrix strips and moved them back to the starting position so that during the succeeding cycle, the roller may be engaged by the cam and the latch dogs be moved into the position shown in Figure 2 so as to make it possible for the matrix strips to go down on the next cycle of operation. It will be noted that the purpose of the springs 15 associated with the latch dogs is merely to provide a convenient and easy means for lifting them out of engagement or for yieldingly limiting or tending to yieldingly limit their angular excursion. The springs, however, do not exert any 20 downward pressure on the dogs, gravity doing that. This arrangement being made in the interest of silence because a spring pressed dog as it clicks over each serration would be very much 25 more noisy than a gravity held dog.

While I have illustrated my invention as applied to a matrix strip wherein a single continuous strip is used having a plurality of characters in intaglio from which type slugs are to be cast, it is obvious that under some circumstances the matrix strip might be divided into a plurality of 30 separate members even one for each character. It is equally obvious that so far as my invention is concerned, it makes no difference whether the characters are in intaglio or relief. If in intaglio, they will be used for casting a slug from which 35 printing will take place later or if in relief they might be used for embossing or printing direct. It is equally obvious that the holding and controlling mechanisms which form the basis of this invention while shown applied directly to 40 the back of the serrated matrix strip might equally well be used with any serrated strip whether, it be matrix strip, printing strip, embossing strip or even a separate propelling strip which 45 does all the work.

In the modified form shown in Figures 9, 10 and 11, it will be noted that instead of having a separate spring member to control each pawl, each pawl D¹ is engaged by a relatively stiff tapered strip G, which strip projects from the rock bar G¹, the means for operating this bar being identical with the means for operating the spring bar D⁶. It will be noted that the pawls are narrower than the matrix and there is a washer G² between each pair of pawls and the 55 pawls are also loose so that they may move back and forth with their washers. The stop plates G³ limit such movement. This is for the purpose of permitting the pawls to have a sufficient freedom of movement to take care of matrix strips of 60 different thicknesses, for instance, the same set of pawls may control strips with which pica or elite or other sized type may be used and it may happen that one pawl may be in line with parts 65 of two matrix strips or that one pawl may be 70

in alignment with one matrix strip only but in no case is there a matrix strip which does not have all or part of a pawl in line with it. Reference to the drawings will show that at one point the tapered strip is in such position that the pawls are free to move up and down by gravity to engage the matrix strips. In another position the pawls are raised out of engagement with the matrix strips to permit them to go down under the influence of the controlling mechanism and in a third position shown in dotted lines in Figure 9, they are so disposed that the pawls are held by the strip yieldingly to be sure against the matrices.

15 The use and operation of my invention are as follows:

The typist writes a line on the typewriter and that automatically sets up a series of pattern pins on the machine. She then pushes a button and the operating levers swing down carrying with them the matrix strip drive bar. Each matrix strip is yieldably held to the bar and as each strip engages its appropriate pattern pin, the bar traveling forward, the yieldable engagement releases, the matrix strip is held in place, the drive bar going down to the bottom of its excursion until each strip has been released and is held by the stop or pattern pin. Then the aligning mechanism comes into operation and aligns the matrices with the letters all in the same line. The squeeze bar engages the matrix strips and the casting or printing act takes place. As soon as this casting or printing act has taken place, the squeeze bar and the aligning mechanism are automatically released and withdrawn. At the same time, the propeller bar comes up engaging successive matrix strips as it reaches them. The automatic detent dog or latch associated with each matrix strip holds the matrix strip against downward movement but offers no opposition to the upward movement of the matrix strip. This is accomplished because the cam which operates the battery of automatic detents, it will be noted is a short cam and only permits or causes movement of the automatic detent strip into working position during the time subsequent to the engagement of the aligning mechanism and to the time subsequent to the completion of the upward excursion of the drive bar. Thus the automatic detents are not in engagement with the matrix strips being held well above them all the time that the matrix strips are going down into printing or casting position.

It will be noted that there is one detent for each matrix strip. These detents are loosely mounted in their supporting bar, being held in place by a loose pivot pin. The spring bar with one spring associated with each detent is rocked by the cam either into the up position when the detents are all raised above the matrices or into the down position when the detents are all permitted under the influence of gravity to engage the backs of the matrices and penetrate the notches therein. No spring pressure is normally used to force the detents against the matrices. The spring is merely for the purpose of providing a smooth and flexible operation of the detents and for the purpose of flexibly limiting their angular excursion up or down as the case may be.

70 I claim:

1. In combination, a plurality of longitudinally movable bars arranged side by side, a driving member and a yielding connection between it and each bar whereby the driving member propels the bars in unison along an inclined path, means in

the path of each bar to arrest it at a predetermined point in its travel as the driving member goes on, means for holding all bars in place after they have been arrested, means for preventing downward movement of the bars after the holding means have engaged them.

2. In combination, a plurality of longitudinally movable bars arranged side by side, a driving member and a yielding connection between it and each bar whereby the driving member propels the bars in unison along an inclined path, means in the path of each bar to arrest it at a predetermined point in its travel as the driving member goes on, means for holding all the bars in place after they have been arrested and means for preventing downward movement of the bars after the holding means have engaged them, the downward movement preventing means comprising a plurality of pivoted dogs adapted to gravitally engage the bars.

3. In combination, a plurality of longitudinally movable bars arranged side by side, a driving member and a yielding connection between it and each bar whereby the driving member propels the bars in unison along an inclined path, means in the path of each bar to arrest it at a predetermined point in its travel as the driving member goes on, means for holding all the bars in place after they have been arrested, and means for preventing downward movement of the bars after the holding means have engaged them, the downward movement preventing means comprising a plurality of pivoted dogs adapted to gravitally engage the bars and means for selectively moving the dogs into and out of working relation with the bars.

4. In combination, a plurality of longitudinally movable bars arranged side by side, a driving member and a yielding connection between it and each bar whereby the driving member propels the bars in unison along an inclined path, means in the path of each bar to arrest it at a predetermined point in its travel as the driving member goes on, means for holding all the bars in place after they have been arrested and means for preventing downward movement of the bars after the holding means have engaged them, the downward movement preventing means comprising a plurality of pivoted dogs adapted to gravitally engage the bars, the bars being serrated where they are engaged by the dogs.

5. In combination, a plurality of longitudinally movable bars arranged side by side, a driving member and a yielding connection between it and each bar whereby the driving member propels the bars in unison along an inclined path, means in the path of each bar to arrest it at a predetermined point in its travel as the driving member goes on, means for holding all bars in place after they have been arrested, means for preventing downward movement of the bars after the holding means have engaged them, the downward movement preventing means comprising a fixed supporting frame, a plurality of dogs loosely pivoted thereon, means removed from the frame for selectively positioning the dogs in and out of working relation with the bars.

6. In combination, a plurality of longitudinally movable bars arranged side by side, a driving member and a yielding connection between it and each bar whereby the driving member propels the bars in unison along an inclined path, means in the path of each bar to arrest it at a predetermined point in its travel as the driving member goes on, means for holding all bars

in place after they have been arrested, means for preventing downward movement of the bars after the holding means have engaged them, the downward movement preventing means comprising a fixed supporting frame, a plurality of dogs loosely pivoted thereon, means removed from the frame for selectively positioning the dogs in and out of working relation with the bars, comprising a rotatable member, a yielding loose connection between the rotatable member and each dog, whereby when the rotating member is in one position the yielding means lift the dogs away from the bars and when in another position the yielding means permit the dogs to engage the bars by gravity.

7. In combination, a plurality of longitudinally movable bars arranged side by side, a driving member and a yielding connection between it and each bar whereby the driving member propels the bars in unison along an inclined path, means in the path of each bar to arrest it at a predetermined point in its travel as the driving member goes on, means for holding all bars in place after they have been arrested, means for preventing downward movement of the bars after the holding means have engaged them, the downward movement preventing means comprising a fixed supporting frame, a plurality of dogs loosely pivoted thereon, means removed from the frame for selectively positioning the dogs in and out of working relation with the bars, the dog controlling means comprising a lever, a cam adapted to rock the lever and yielding means adapted to resist movement of the lever in response to the cam.

8. In combination, a plurality of longitudinally movable bars arranged side by side, a driving member and a yielding connection between it and each bar whereby the driving member propels the bars in unison along an inclined path, means in the path of each bar to arrest it at a predetermined point in its travel as the driving member goes on, means for holding all bars in place after they have been arrested, means for preventing downward movement of the bars after the holding means have engaged them, the downward movement preventing means comprising a fixed supporting frame, a plurality of dogs loosely pivoted thereon, means removed from the frame for selectively positioning the dogs in and out of working relation with the bars, comprising a rotatable member, a yielding loose connection between the rotatable member and each dog, whereby when the rotating member is in one position the yielding means lift the dogs away from the bars and when in another position the yielding means permit the dogs to engage the bars by gravity, the dog controlling means comprising a lever, a cam adapted to rock the lever and yielding means adapted to resist movement of the lever in response to the cam.

9. In combination, a plurality of longitudinally movable bars arranged side by side, a driving member and a connection between it and each bar whereby the driving member moves the bars in unison along an inclined path, means in the path of each bar to arrest it at a predetermined point in its travel as the driving member goes on, the driving member being adapted thereafter to return to pick up successive bars and automatic means operative after the bar has been arrested for preventing downward movement of the bars.

10. In combination, a plurality of longitudinally movable bars arranged side by side, a driving

member and a connection between it and each bar whereby the driving member moves the bars in unison along an inclined path, means in the path of each bar to arrest it at a predetermined point in its travel as the driving member goes on, the driving member being adapted thereafter to return to pick up successive bars and means for selectively positioning the downward movement preventing means into and out of working relation with the bars.

11. In combination, a plurality of longitudinally movable bars arranged side by side, a driving member and a connection between it and each bar whereby the driving member moves the bars in unison along an inclined path, means in the path of each bar to arrest it at a predetermined point in its travel as the driving member goes on, the driving member being adapted thereafter to return to pick up successive bars and an over-running clutch for preventing the downward movement of the bars.

12. In combination, a plurality of longitudinally movable bars arranged side by side, a driving member and a connection between it and each bar whereby the driving member moves the bars in unison along an inclined path, means in the path of each bar to arrest it at a predetermined point in its travel as the driving member goes on, the driving member being adapted thereafter to return to pick up successive bars and an over-running clutch for preventing the downward movement of the bars, and means for positioning the over-running clutch in working relation with the bars after the bars have been arrested and for subsequently removing the over-running clutch from working relation with the bars after all the bars have again been picked up by the driving member.

13. In combination, a plurality of longitudinally movable bars arranged side by side, a driving member and a yielding connection between it and each bar whereby the driving member propels the bars in unison along an inclined path, means in the path of each bar to arrest it at a predetermined point in its travel as the driving member goes on, means for holding all the bars in place after they have been arrested and means for preventing downward movement of the bars after the holding means have engaged them, the downward movement preventing means comprising a plurality of pivoted dogs and means for causing said dogs to engage the bars.

14. In combination, a plurality of longitudinally movable bars arranged side by side, a driving member and a yielding connection between it and each bar whereby the driving member propels the bars in unison along an inclined path, means in the path of each bar to arrest it at a predetermined point in its travel as the driving member goes on, means for holding all the bars in place after they have been arrested and means for preventing downward movement of the bars after the holding means have engaged them, the downward movement preventing means comprising a plurality of pivoted dogs and means for causing the dogs to engage the bars, the bars being serrated where they are engaged by the dogs.

15. In combination, a plurality of bars arranged loosely side by side for longitudinal movement, a driving member and a releasable connection between it and each bar whereby it may move all of them in unison along an inclined path, means in the path of each bar to arrest it in a predetermined point in its travel as the driving

- member goes on, the driving member being adapted thereafter to return to pick up successive bars, the bars being serrated along one edge, a plurality of loosely pivoted dogs arranged in successive groups adapted to engage such serrations, the dogs being free to move along their pivot axes in a direction perpendicular to the line of movement of the bars, means interposed between successive groups of dogs for positively limiting their perpendicular movement.
16. In combination, a plurality of bars arranged loosely side by side for longitudinal movement, a driving member and a releasable connection between it and each bar whereby it may move all of them in unison along an inclined path, means in the path of each bar to arrest it in a predetermined point in its travel as the driving member goes on, the driving member being adapted thereafter to return to pick up successive bars, the bars being serrated along one edge, a plurality of loosely pivoted dogs arranged in successive groups adapted to engage such serrations, the dogs being free to move along their pivot axes in a direction perpendicular to the line of movement of the bars, means interposed between successive groups of dogs for positively limiting their perpendicular movement, and means for selectively positioning said dogs into and out of working relation with respect to the bars, said means comprising a pivoted control strip extending across the total width of all the bars and a cam and spring drive mechanism therefor, the dogs being notched to be engaged by said strip.
17. In combination, a plurality of bars arranged loosely side by side for longitudinal movement, a driving member and a releasable connection between it and each bar whereby it may move all of them in unison along an inclined path, means in the path of each bar to arrest it in a predetermined point in its travel as the driving member goes on, the driving member being adapted thereafter to return to pick up successive bars, the bars being serrated along one edge, a plurality of loosely pivoted dogs arranged in successive groups adapted to engage such serrations, the dogs being free to move along their pivot axes in a direction perpendicular to the line of movement of the bars, means interposed between successive groups of dogs for positively limiting their perpendicular movement, means for selectively positioning said dogs whereby they are sometimes held positively but yieldingly in engagement with the bars and other times held out of engagement with the bars and at other times so positioned that they may engage the bars gravitally.
18. In combination, a plurality of bars arranged loosely side by side for longitudinal movement, a driving member and a releasable connection between it and each bar whereby it may move all of them in unison along an inclined path, means in the path of each bar to arrest it in a predetermined point in its travel as the driving member goes on, the driving member being adapted thereafter to return to pick up successive bars, the bars being serrated along one edge, a plurality of loosely pivoted dogs arranged in successive groups adapted to engage such serrations, the dogs being free to move along their pivot axes in a direction perpendicular to the line of movement of the bars, means interposed between successive groups of dogs for positively limiting their perpendicular movement, and means for selectively positioning said dogs into and out of working relation with respect to the bars, said means comprising a pivoted control strip extending across the total width of all the bars and a cam and spring drive mechanism therefor, the dogs being notched to be engaged by said strip.
19. In combination, a plurality of bars arranged loosely side by side for longitudinal movement, a driving member and a releasable connection between it and each bar whereby it may move all of them in unison along an inclined path, means in the path of each bar to arrest it in a predetermined point in its travel as the driving member goes on, the driving member being adapted thereafter to return to pick up successive bars, the bars being serrated along one edge, a plurality of loosely pivoted dogs arranged in successive groups adapted to engage such serrations, the dogs being free to move along their pivot axes in a direction perpendicular to the line of movement of the bars, means interposed between successive groups of dogs for positively limiting their perpendicular movement, means for selectively positioning said dogs whereby they are sometimes held positively but yieldingly in engagement with the bars and other times held out of engagement with the bars and at other times so positioned that they may engage the bars gravitally, said means comprising a pivoted control strip extending across the total width of all the bars and a cam and spring drive mechanism therefor, the dogs being notched to be engaged by said strip.

GEORGE HERBERT WHITE.
